(57) **CLAIM**

The ornamental design for a snow and ice removal device for automobile exhaust pipe, as shown and described.

DESCRIPTION

FIG. 1 is a perspective view of a snow and ice removal device for automobile exhaust pipe showing my new design;

FIG. 2 is a side view (opposite view is mirror image) thereof;

FIG. 3 is a front view thereof;

FIG. 4 is a back view thereof;

FIG. 5 is a top view thereof; and,

FIG. 6 is a bottom view thereof.
